UNITED STATES PATENT OFFICE

MICKOLAS DZIEDZIC AND JOHN E. COVEY, OF CHICAGO, ILLINOIS, ASSIGNEES TO SWIFT & COMPANY, OF CHICAGO, ILLINOIS, A CORPORATION OF ILLINOIS

SKEWER BLOCK

Application filed December 20, 1928. Serial No. 327,276.

This invention relates to an improved bacon skewer device for shaping and crowding the sides of bacon into the desired, substantially rectangular form.

The main objects of this invention are to provide a power-driven, shaping device of the class described which may be suitably adapted for shaping sides of bacon of various degrees of firmness; to provide extensible compressing members having a defined course of movement for shaping sides of bacon; to provide pneumatic actuating mechanism for automatically effecting preliminary extension of the slide bars and subsequent movement thereof towards each other for avoiding the occurrence of irregular formations on the edges of the side of bacon and for effecting preliminary retraction of the extensible elements of the compressing members and subsequent outward movement of the latter after the shaping operation, to avoid confliction between the slide bars and a bacon hanger which is generally attached to the bacon while the latter is compressed, and to provide self-adjusting, end-forming means having a limited freedom of pivotal movement for adapting it to form the end of a side of bacon cut from either side of a hog.

An illustrative embodiment of our invention is shown in the accompanying drawings, in which:

Figure 1 is a front elevation.

Fig. 2 is a fragmentary top plan.

Fig. 3 is a section taken on the line 3—3 of Fig. 1.

Fig. 4 is a section taken on the line 4—4 of Fig. 1.

Fig. 5 is a fragmentary section taken on the line 5—5 of Fig. 4.

Fig. 6 is an enlarged fragmentary perspective of a compressing member.

The above objects are attained by means of the device illustrated in the accompanying drawings which show a table having extensible slide bars or compressing members slidably mounted thereon and an end forming element pivotally mounted on the table in advance of the forward ends of the slide bars. Pivotal movement of the end-

forming element is limited by upright pins which allow the same to pivot substantially an equal amount in both directions.

Each compressing member comprises a vertical portion, a horizontal portion and an extensible element slidably mounted on the former. A rack bar is fixed to the bottom side of each horizontal portion of the compressing members by spaced bolts and is located below the surface of the table.

Actuating mechanism, comprising two cylinders arranged with their longitudinal axes substantially in alignment, is mounted on the front end of the table. Each cylinder is equipped with a separate and independent piston and piston rod.

The compressing members are operatively connected with pneumatic actuating mechanism comprising two separate cylinders and pistons, one for extending and retracting the compressing members and the other for moving the same together and apart for crowding the edge portions of a side of bacon.

The pipe system through which a compressed medium, preferably air, is supplied to the cylinders comprises a two-way valve for each cylinder for alternatively admitting compressed air to the top and bottom thereof. The valve that admits compressed air to the cylinder containing the piston that extends and retracts the compressing members is operatively connected with a foot pedal by means of which it may be opened and closed and the valve associated with the other cylinder is operatively connected with the piston rod of the first-mentioned cylinder in such a manner as to cause the compressing members to be moved together after the extensible elements thereof have been projected and to be urged apart after said extensible elements have been retracted.

A third valve is provided in the compressed air distributing system for exhausting some of the air to reduce the pressure thereof and correspondingly reduce the compressing force of the compressing members. This valve is actuated by a foot lever having its bottom end located in close proximity to the foot pedal, so that both the pedal and the lever may be moved at the same time.

In the forms shown in the drawings, the table 1, or supporting structure, is provided with spaced, slidably mounted, compressing members, comprising a vertical portion 2 and a horizontal portion 3. The horizontal portion 3 is provided on its bottom side with a rack bar 4 having a projection 5 on its upper side which extends into slots formed in the table 1 for guiding the movement of the compressing members. A carriage 6 is slidably mounted on the table, or supporting structure, below the top thereof. This carriage comprises a frame having spaced side members which are slidably engaged in slots formed in the angle irons 7 and 8, as shown in Fig. 4. Stopping means, comprising a metal strip 9 having flanges on its forward and rearward extremities, are secured to the bottom of the side portions of the carriage in position to abut against the angle members 7 and 8 for limiting the forward and rearward movements respectively of the carriage 6.

Extensible bars 10 are slidably mounted on the adjacent faces of the vertical portions of the compressing members, as shown in Fig. 6. Each extensible bar is provided with a downwardly extending pin 11 which extends into an elongated slot in the carriage 6, so that when the carriage 6 is extended and retracted the members 10 are likewise extended and retracted.

Pneumatic actuating mechanism, comprising upper and lower cylinders 12 and 13 respectively, mounted substantially in vertical alignment, is provided for effecting preliminary extension of the compressing members and subsequent movement thereof towards each other. The upper and lower cylinders are provided with pistons 14 and 15 respectively and the upper piston is provided with a piston rod 16 which has rack teeth 17 on its upper end. The lower piston 15 is provided with a downwardly extending piston rod 21. A pinion 18 mounted on the supporting structure 1 meshes with the rack teeth 17 of the upper piston rod 16. A bell crank, comprising arms 19 and 20, is rigidly attached to the pinion 18. The arm 20 of the bell crank operatively connects with the carriage 6, for projecting and retracting the latter.

The lower piston rod 21 is rigidly attached to a rack bar 22 which is provided, at its upper end, with rack teeth 23 on one side and 24 on the other. The rack teeth 23 and 24 of the bar 22 mesh with spaced pinion segments 25 and 26 respectively which in turn mesh with the teeth of the rack bars 4 of the compressing members.

An end plate or wall 38 is pivotally mounted on the table 1 in advance of the forward extremities of the compressing members and is free to rotate about a substantially verti-

cal axis 39 within limits set by spaced stops or pins 40.

Compressed air is supplied to the cylinders from the conduit 27 through pipe system 28. A two-way valve 29 is provided in the pipe system 28 for discharging the compressed air, either into the top of the top cylinder 12 or the bottom thereof. The pipe system 28 also comprises a two-way valve 30 for controlling the flow of compressed air to the top and bottom of the lower cylinder 13 respectively.

The valve 30 is operatively connected to the arm 19 of the bell crank lever by a link 31. The valve 29 is provided with actuating mechanism comprising a foot pedal 32 operatively connected to the valve 29 by a lever 33 and a link rod 34. A release valve 35 is also included in the pipe system 28 for reducing the pressure of the air therein when it is desired to reduce the compressive force of the slide bars. The valve 35 is regulated by a lever 36 pivoted to the supporting structure of the table and connected with the valve by links 37. The lower end of the lever 36 is provided with a flange 38 located in close proximity to the foot pedal, so that it may be engaged by a side-wise movement of the pedal while the same is moving down. When the valve 35 is opened by the movement of the lever 36, some of the air in the pipe system is allowed to escape and the air pressure in the lower cylinder 13 is reduced.

When the device is in operation, the foot pedal 32 is normally in its upper position and the valves 29 and 30 are set to admit air into the top of the cylinder 12 and the bottom of the cylinder 13 respectively. The compressing members are retained in their outermost position and the extensible elements thereof are retracted. When the pedal 32 is depressed the valve 29 is reset to admit air into the bottom of the upper cylinder 12 and exhaust air from the top thereof. The rack 17 is moved upwardly rotating the pinion 18, projecting the carriage 6 and the extensible elements 10 connected therewith and resetting the valve 30 by movement of the link 31, to admit air into the top of the lower cylinder 13 and exhaust air from the bottom thereof. The piston 15 of the lower cylinder 13 is moved downwardly, together with the piston rod 21 and the rack bar 22 attached thereto, rotating the pinion segments 25 and 26 and thereby moving the compressing members towards each other. When the pedal 32 is released, it is moved to its upper position by the action of the spring 41 and the valve 21 is reset in its starting position. The extensible elements 10 are retracted and there-after the valve 30 is reset to its starting position and the compressing members 10 are moved apart.

Although but one specific embodiment of this invention has been herein shown and described, it will be understood that numerous details of the construction shown may be altered or omitted without departing from the spirit of this invention as defined by the following claims.

We claim:

1. A skewer block of the class described comprising a supporting structure, extensible compressing members mounted on said supporting structure and movable relative thereto, and means for automatically extending said members in one operation and subsequently moving the same toward each other in a separate operation.

2. A skewer block for shaping the sides of bacon, comprising a supporting table, movable extensible members mounted on said table for crowding the edge protions of a side of bacon into a predetermined shape, and pneumatic actuating means associated with said extensible member comprising means for effecting a preliminary extension thereof and a subsequent movement thereof towards each other.

3. A skewer block for shaping meat, comprising a table, extensible compressing members movably mounted on said table, an end-forming element pivotally mounted on said table for straightening the end of a side of bacon, and pneumatic means for effecting preliminary extension of said compressing members and subsequent movement thereof towards each other for crowding the edges of a side of bacon into a substantially rectangular shape, said bars being retracted form the proximity of said end-forming member by said pneumatic means before the bars are moved relative to each other to avoid confilction between the latter and a bacon hanger.

Signed at Chicago this 17th day of December, 1928.

MICKOLAS DZIEDZIC.
JOHN E. COVEY.
